UNITED STATES PATENT OFFICE.

JAMES J. LAWLER, OF MOUNT VERNON, NEW YORK.

DESIGN FOR A WATER-HEATER.

No. 38,892.

Specification for Design.

Patented Nov. 19, 1907.

Application filed August 24, 1907. Serial No. 390,057. Term of patent 14 years.

To all whom it may concern:

Be it known that I, JAMES J. LAWLER, a citizen of the United States, and resident of Mount Vernon, in the county of Westchester and State of New York, have invented a certain new, original, and ornamental Design for a Water-Heater, of which the following is a specification, reference being had to the accompanying drawing, forming part thereof.

The drawing represents a perspective view of a water heater showing my new design.

I claim:—

The ornamental design for a water heater as shown.

JAMES J. LAWLER.
